LOOM STOPPING MEANS

Philemon Munroe, New Bedford, Mass., assignor
to Hoosac Mills Corporation, a corporation of
Massachusetts

Application June 24, 1952, Serial No. 295,167

10 Claims. (Cl. 139—377)

1 This invention relates to a loom stopping means.

It is common practice in automatic looms to have the filling battery at one end portion of the loom, usually the right-hand end, and the filling fork mechanism at the other end portion of the loom. When the shuttle has been picked from the shuttle box at the battery end of the loom and there is an absence of filling in the shed, upon forward movement of the lay the filling fork mechanism will act to stop the loom as the lay approaches back center on the backward movement of the lay. The shuttle on the said backward movement will be picked out of the left-hand shuttle box to be lodged into the right-hand shuttle box when the loom stops. This is undesirable since the shuttle cannot be readily retrieved from the said right-hand shuttle box because of the obstruction of the said battery. The weaver usually has to set the loom in motion for a pick thereof to drive the said shuttle out of said right-hand shuttle box.

The general object of the invention is to provide a filling stop motion which will upon filling failure, operate to stop the loom as the lay 25 approaches back center and the shuttle is positioned in the shuttle box at the end of the loom opposite to the battery side thereof.

Another object is to provide means associated with the filling fork mechanism to be operated thereby to set the warp stop motion knock-off mechanism into action to stop the loom upon filling failure.

Another object is to provide means associated with the filling fork mechanism, which after being set into action upon filling failure, will be reset and held in operative position by a movement of the loom shipper handle to an "on" position.

A more specific object of the invention is to provide for delayed action transmission in the usual filling fork motion for actuating the stopping of the loom one pick after detection of filling failure.

With these and other objects in view, the invention consists of certain novel features of construction as will be more fully described and particularly pointed out in the appended claims.

In the accompanying drawings:

Figure 1 is a top plan view of a portion of a loom embodying my invention;

Figure 2 is a top plan view of the filling fork mechanism shown in Figure 1 and on an enlarged scale;

Figure 3 is a top plan view of a fragmentary 55 portion of the mechanism shown in Figure 2 but with certain elements shown in different relation;

2 Figure 4 is a similar view but showing the elements of the said mechanism in a still further different relation;

Figure 5 is a fragmental sectional view taken along line 5—5 of Figure 2;

Figure 6 is a similar view showing a different relationship of the parts shown in Figure 5;

Figure 7 is a view partially in section and taken substantially along lines 7—7 of Figure 6;

Figure 8 is a side elevational view of the warp stop motion knock-off mechanism looking from the left of Figure 1;

Figure 9 is a side elevational view partly in section of the filling fork mechanism looking from the opposite direction from Figure 8; and

Figure 10 is a sectional view taken along line 10—10 of Figure 8 and on an enlarged scale.

Referring to the drawings, particularly Figure 1, 10 designates a portion of a loom at the side opposite the filling battery (usually the left-hand side) of a general construction well known and familiar to those skilled in the art, which comprises a frame, a portion of one side 11 of which is shown. The side frames 11 are connected by a breast beam 12 over which the cloth *c* being woven passes to be advanced and packaged by cloth take-up mechanism. The loom has swords 13 which support a reciprocating lay 14 which is provided at each end with a shuttle box 15. As the lay 14 is reciprocated, the filling carrier or shuttle 16 will be picked out of a shuttle box 15 by means of a picker 17 to send the shuttle in flight across the shed 13 to be boxed in the opposite shuttle box, all in a usual manner.

The loom is also provided with a usual warp stop motion, not shown, but well known in the art, which acts upon a warp failure to set into motion a so-called knock-off mechanism designated generally 19 (see Figure 8). This knock-off mechanism comprises a knock-off finger 20 which is pivoted as at 21 to the end 22 of a rod 23. This finger 20 is urged to move toward an inoperative position, shown in full lines by shading, by means of a compression spring 24. The other end of the rod 23 is provided with an arm 25 having a slotted opening 26 therethrough in which is received a pin 27 projecting from the shipper lever 28 which is pivotally mounted by a stud 29 on a bracket 30 attached to the end of the breast beam 12. This bracket 30 has a stop 31 for engaging the shipper 28 when in the "on" position and a stop 32 for engaging the lever 28

when in the "off" position, as shown in dot and dash lines (see Figure 8).

The other end of the rod 23 is pivotally attached to a so-called knock-off bracket 33 by means of links 34 which are pivotally attached at one end to the said bracket as at 35. The other end of the links is attached to the said pivot 21 for the finger 20. Upon a warp failure such as the breaking thereof, the warp stop motion will be set into motion, which motion will through a flexible connection 90 move the finger 20 upwardly about the pivot 21 to place the same, as shown in dot and dash line in Figure 8, in the path of a bunter or knock-off 36 which is attached to the lay 14 as by means of bolts 37. The connection 90 is a flexible cable having a plunger 91 (see Figure 10) through which linear motion is transmitted to a sliding pin 92 housed within the bracket 33 and biased into engagement with the said plunger 91 by means of a spring 93. The pin 92 extends into engagement with the finger 20 and will swing the same upwardly as previously stated.

Upon said finger 20 being engaged by the bunter 36, the rod 23 will be moved thereby in the direction of the rearward movement of the lay to swing the end 22 about the pivot 35 and thereby exert a pull on the shipper 28 to rock the same about the stud 29 to the "off" position shown in the said dot and dash line (see Figure 8). This motion of the lever 28 will be transmitted through a brake rod 38 which is pivotally attached as at 40 to the shipper 28, while the other end of this brake rod is attached to a brake lever 41 rockable about a stud fastening 42, which upon rocking of said lever 41 through mechanism connected to said lever 41 will function to declutch the loom from its drive and apply the brake, not shown, to bring the loom to rest.

The filling fork mechanism designated generally 43 (see Figures 1 and 2) is mounted on the breast beam 12 at the left-hand side of the loom or that side opposite to the filling battery, not shown, and includes a filling fork slide 44 which pivotally carries filling fork 45. The slide 44 is moved by the usual mechanism including filling motion cam 46 (see Figure 9) mounted on a shaft 47 which rotates one revolution to two revolutions of the crank shaft and is engaged by a cam follower 48 mounted on an arm 49 rockable about a pivot 50. This arm 49 is provided with a portion 51 which extends on the opposite side of the pivot 50 and carries a filling motion hook 52 which is engageable by the loop 53 of the filling fork 45 so as to slidably move the slide 44 in the filling motion stand 56. The slide 44 is normally maintained in its backward position by means of a pull spring 57 (Figure 2) herein shown as being attached to the slide as at 58 and to the stand 56 as at 59. The filling fork 45 is weighted to have the loop 53 thereof normally at a position to be engaged by the hook 52. When the lay moves forward, the tangs 60 (see Figure 9) of the filling fork will be engaged by the filling F and tilted about its pivot to raise the filling F and tilted about its pivot to raise the loop 53 out of the path of the oscillation hook 52. If no filling F is present in the shed, the fork 45 will not be tilted and the loop 53 will be engaged by the filling motion hook 52 to move the slide 44 in the direction toward the breast beam. This movement of the slide 44 toward the breast beam is usually transferred to a leverage system (not shown) which operates to shift the shipper 28 from the "on" to the "off" position to stop the loom. The elements of the filling fork motion

mechanism and the motion so far described are usual and well known.

In the present embodiment of the invention, the usual means associated with the filling fork slide to throw or shift the shipper from the "on" to the "off" position are omitted and an arm 61 having a right angular bend 62 cut on a slant 63 (see Figure 7) is pivotally mounted on the slide 44 as at 64. A rod 65 (Figure 2) is suitably mounted on a bracket 66 which is attached to the upper side of the breast beam 12 as by means of bolts and nut fastenings 67. This bracket 66 carries a bearing 68 which has an opening 69 to axially slidably receive the rod 65. This rod 65 has an 10 abutment 70 attached at one end thereof which is provided with a cam surface 72 and a compression spring 71 encircling the rod 65 and acting between the said abutment 70 and the adjacent edge of the bearing 68 tends to move the rod 65 outwardly or toward the shipper lever 28. This abutment with the loom in motion engages against the shipper 28 and when the shipper is moved to the "off" position, the rod 65 under urge of spring 71 will be moved outwardly until stop collar 25 73 which is secured to the rod 65 on the opposite side of the bearing 68 engages the bearing 68 and limits the outward movement of the said rod 65. When the loom is placed in motion by pulling the shipper 28 to the "on" position, the shipper 30 will engage the surface 72 to move the rod 65 to its "on" position as shown in Figures 2 and 3.

The rod 65 also mounts a support 74 which carries the end member 75 of a flexible cable 76 which is similar to the said cable 90. This member 75 has a plunger 77 which projects outwardly at such a location that when the shipper handle is in the "on" position, it will be engaged by the end 62 of the arm 61 upon a forward movement of the said slide 44 (see Figures 2 and 3). The other end of the flexible cable 76 is also attached to the bracket 33 as by means of a nut fastening 78 (Figure 10) and its plunger end 79 (see Figure 10) engages a pin 92' extending into engagement with the finger 20 and biased into engagement with plunger end 79 by means of a spring 93'. Thus motion of the plunger 77 will be transmitted through the cable 76 to rock or raise the finger 20 to actuate the said knock-off.

Assuming the loom to be in motion with an absence of filling F in the shed 18 and at the present instance the shuttle lodged in the left-hand shuttle box, the lay 14 at back center moving towards front center through bottom center, the cam follower 48 engaging the dwell on the low side of the cam 46 which is turning counterclockwise (see Figure 9), the arm 61 will be at its normal position inwardly of the free end of the plunger 77 and the slanted face 63 of the arm 61 will be resting upon the plunger 77 (see Figures 1 and 6). Upon the forward movement of the lay or from back center to front center through bottom center, the filling fork 45 will remain stationary because of the said absence of filling F in the shed 18 and the loop 53 thereof will be in the path of the hook 52 carried by the arm or hub 49 which is being rocked in a counterclockwise direction about the pivot 50 by the now rising cam 46. As the lay 14 passes front center and moving towards top center, the hook 52 will engage the loop 53 of the filling fork 45 and further movement of the hook 52 in the same direction will move the slide 44 towards the breast beam in the manner previously stated and hold said slide 44 at said forward position against the action of the spring 57 during the dwell on the

high side of the cam in the usual manner. The finger 61 will be carried by the slide beyond the end of the plunger 77, which finger upon being free of the plunger 77 will swing downwardly by gravity to the full-line position shown in Figures 2 and 5 to be at a position to engage the plunger 77 on the return movement of the slide 44. A stop pin 80 (Figure 5) may be provided to limit the downward swing of said arm 61. As the lay 14 approaches top center, the shuttle will be picked out of the left-hand shuttle box to be sent in flight across the shed 18 to be lodged in the right-hand shuttle box. As the lay continues moving in the same direction through back center and then forwardly through bottom center, the cam 46 will be turning towards the low side thereof causing a reversed or clockwise rocking movement of the arm 49 about the pivot 50 to move the hook 52 away from the breast beam 12 and the slide under the urge of the spring 57 to move to its normal or original position. As the slide 44 is being moved towards the said original position, the arm 61 carried thereby will engage and move the plunger inwardly (see Figure 3) to transmit the return motion of said slide 44 to the pin 92' to raise the finger 20 in position to be engaged by the bunter 36. The finger is moved in the said raised position after the lay 14 has passed the same in the forward movement thereof. The lay 14 will continue to move in the same direction past front center and towards back center through top center. As the lay 14 again approaches top center, the shuttle will be picked out of the right-hand shuttle box to be sent in flight across the shed 18 to be lodged in the left-hand shuttle box and the bunter 36 will engage the raised finger 20 to pull the shipper 28 from the on position to the off position to declutch and apply the brake on the loom as the lay is approaching back center. It will now be seen that the filling fork mechanism operates to delay the action of stopping the loom one pick upon filling failure by reason of the operating action to stop the loom taking place as the filling slide 44 returns to its normal position rather than heretofore on its motion toward the breast beam, thus providing for returning of the shuttle into the shuttle box at that end of the lay at which the filling detection took place.

When the shipper is moved to the "off" position, the rod 65 under urge of spring 71 will be moved outwardly as seen in Figures 4 and 7 to position the plunger 77 beyond the end of the arm 62. Upon movement of the shipper 28 to the "on" position, the same will engage the surface 72 of the abutment 79 and push the rod 65 inwardly. The plunger 77 carried thereby will engage the slanted or cam surface 63 of the arm 62 to swing the same upwardly so as to rest on said plunger 77 as previously described.

I claim:

1. In a loom, a lay, an abutment on said lay, a filling fork detecting mechanism including a filling fork, a slide on which said fork is pivoted, a knock-off operable to stop the loom and adapted to be positioned in and out of the path of movement of said abutment, means for moving said slide in one direction upon filling failure, resilient means for returning said slide in the other direction, and means connected to said knock-off operated by the return movement of said slide to position said knock-off in the path of said abutment to be engaged thereby to be moved to stop the loom.

2. In a loom, a reciprocating lay, a filling fork

detecting mechanism operated upon filling failure to stop the loom, said mechanism including a filling feeling fork, a slide on which said fork is pivoted, means adapted to engage said filling fork for moving said slide in one direction upon filling failure, resilient means for returning said slide in the other direction, an abutment carried by said lay, a knock-off movably mounted and operated by engagement with said abutment to stop the loom and adapted to be positioned in and out of the path of movement of said abutment, and motion transmitting means connected to said knock-off for transmitting the motion of said slide to move said knock-off in the path of said abutment during the return movement of said slide.

3. In a loom, a warp stop motion operated upon warp failure to stop the loom, a filling feeling fork, a slide on which said fork is pivoted, rockable means adapted to engage said filling fork for moving said slide in one direction upon filling failure, resilient means for returning said slide in the other direction, and means carried by said slide operatively connecting said warp stop motion to said slide to actuate said warp stop motion during the return movement of said slide.

4. In a loom, a warp stop motion operated upon warp failure to stop the loom, a filling feeling fork, a slide on which said fork is pivoted, rockable means adapted to engage said filling fork for moving said slide in one direction upon filling failure, resilient means for returning said slide in the other direction, an arm pivotally mounted on said slide to move therewith, means operatively connected to said warp stop motion and having a plunger positioned in the path of said arm and engageable thereby to transmit the motion of said slide to said warp stop motion to actuate the same during the return movement of said slide.

5. In a loom, a warp stop motion operated upon warp failure to stop the loom, a filling feeling fork, a slide on which said fork is pivoted, rockable means for moving said slide in one direction upon filling failure, resilient means for returning said slide in the other direction, an arm pivotally mounted on said slide to move therewith, a support slidably mounted, a flexible motion transmitting means carried by said support and movable thereby and into the path of said arm and operatively connected to said warp stop motion, said motion transmitting means having a plunger thereon engageable by said arm to transmit the motion of said slide to said warp stop motion to actuate the same during the return movement of said slide.

6. In a loom, a warp stop motion operated upon warp failure to stop the loom, a filling feeling fork, a slide on which said fork is pivoted, means for moving said slide in one direction upon filling failure, resilient means for returning said slide in the other direction, means for transmitting the motion of said slide to said warp stop motion to actuate the same including a plunger, an arm movably mounted on said slide and normally resting on said plunger and carried by said slide beyond said plunger in the movement of said slide in the said one direction, said arm moving in line with said plunger when free thereof to be in position to engage the plunger during the return movement of said slide to actuate said warp stop motion.

7. In a loom, a shipper lever movable to an "on" and "off" position, a warp stop motion operated upon warp failure to stop the loom, a filling feeling fork, a slide on which said fork is pivoted,

means for moving said slide in one direction upon filling failure, resilient means for returning said slide in the other direction, means for transmitting the motion of said slide to said warp stop motion to actuate the same including an arm carried by said slide, motion transmitting means including a plunger engageable by said arm for transmitting the motion of said slide to said warp stop motion to actuate the same, a slidable support on which said plunger is secured, said support having an abutment thereon engageable against said shipper lever when in the "on" position to hold said plunger in position to be engaged by said arm and resilient means for moving said support to move said plunger out of said position when said abutment is free of said shipper lever upon the movement thereof to the "off" position.

8. In a loom as set forth in claim 7 further comprising a cam surface on said abutment engageable by said shipper lever to move said support to initial position upon moving said shipper lever to the "on" position.

9. In a loom, a filling fork detecting mechanism including a filling feeling fork, a slide on which said fork is pivoted, a knock-off operated to stop the loom, means for moving said slide in one direction upon filling failure, resilient means for returning said slide in the other direction, a rockable arm carried by said slide and having a cam surface thereon, means for transmitting the

movement of said slide to said knock-off to actuate the same including a plunger, said arm normally resting on said plunger and movable beyond the same and in line therewith upon the movement of said slide in the said one direction, said arm engaging said plunger on the return movement of said slide to transmit the return movement of said slide to actuate said knock-off.

10. In a loom, a loom stop means including a knock-off, an abutment carried by the loom lay and adapted to engage said knock-off to move the same to stop the loom, a filling slide detector movable in one direction upon filling failure, spring means for returning said slide in the other direction, a plunger connected to said knock-off for moving the same into the path of said abutment, and a rockable finger carried by said slide for engaging said plunger to move the same on the said return movement of said slide to position said knock-off in the path of movement of said abutment.

PHILEMON MUNROE.
